UNITED STATES PATENT OFFICE

EDWARD B. WILDER AND WENTWORTH WILDER, OF ST. LOUIS, AND BRYDON BERTRAM BAKER, OF UNIVERSITY CITY, MISSOURI, ASSIGNEES TO WILDER MANUFACTURING COMPANY, OF ST. LOUIS, MISSOURI, A CORPORATION OF MISSOURI

TOY AIRPLANE

Application filed December 30, 1929. Serial No. 417,384.

This invention relates to toy airplanes, and with regard to certain more specific features, to toy airplanes of the self-propelling type.

Among the objects of this invention may be noted the provision of a toy airplane of the self-propelling type which is capable of sustained flight of more than several minutes duration; an airplane of the type described which is characterized by its lightness in weight and strength of construction; an airplane of the type described which simulates in appearance a real airplane; a toy airplane which can readily be adjusted to perform "stunts" characteristic of real airplanes, including changes in vertical and horizontal flight; a toy airplane of the class described which is easily assembled and disassembled, and which, when disassembled, occupies a minimum of storage space; a toy airplane of the class described which will not be irreparably damaged by crashes; and a toy airplane of the class described which is cheaply and easily fabricated, requiring a minimum of special tools and the like. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

In the accompanying drawings, in which is illustrated one of various possible embodiments of the invention,

Fig. 1 is a top plan view of the assembled airplane;

Fig. 2 is a side elevation of the assembled airplane;

Fig. 3 is a front elevation of the assembled airplane;

Fig. 4 is a fragmentary side elevation of the front end of the assembled airplane, showing certain parts in section and certain parts in detail;

Fig. 5 is a fragmentary side elevation of the rear end of the assembled airplane;

Fig. 6 is a fragmentary top plan view of

the rear end of the assembled airplane showing the adjustment of certain parts;

Fig. 7 is a perspective view of a landing gear saddle;

Fig. 8 is a perspective view of a saddle;

Fig. 9 is a front view of a propeller; and,

Fig. 10 is a section taken substantially on line 10—10 of Fig. 9.

Similar reference characters indicate corresponding parts throughout the several views of the drawings.

Referring now more particularly to Fig. 1, there is illustrated at numeral 1 a body or fuselage, upon which the remainder of the airplane is mounted. The fuselage 1 preferably comprises a stick of wood of rectangular cross-section, of sufficient strength to withstand the strains to which it will be put as described hereinafter. The dimensions of the fuselage depend entirely upon the size of the toy airplane.

Mounted on the front end of the fuselage 1 is a propeller support 3, which is preferably die-cut from sheet metal, in one piece. The support 3, as shown in Fig. 4, comprises a socket portion 5, which is clamped on to the fuselage 1, and a downwardly extending tab 7. The tab 7 has folded ribs 9 along the sides thereof to strengthen it. It is desirable that the ribs 9 engage or abut the ends of the socket portion 5, so that the tab 7 is rigid in relation to said socket 5. In the lower portion of said tab 7 is pressed a boss or hemispherical raised portion 11, which serves to form a propeller bearing. Through the center of the boss 11 is a hole 13 to accommodate a propeller shaft 15 to be described.

A propeller 17 is illustrated in Fig. 9. It is preferably stamped from sheet metal, and for lightness, aluminum is most desirable. The propeller 17 comprises two blades 19 which are joined by a central portion 21. The blades 19 are given the customary propeller shape and pitch. The central portion 21 has pressed therein, parallel to the blades, a pair of strengthening ribs 23. The ribs 23 serve as a brace to prevent the propeller 17 from bending at the central portion 21. A central hole 25 permits the passage of the propeller shaft 15. A boss 27 is

pressed on the rear side of the propeller 17. Tabs 29 are stamped from the central portion 21 of the propeller 17 to secure said shaft 15 in position. Before assembly, these tabs 29 stand at right angles to the surface 5 of the propeller.

The boss 17 is in bearing contact with the boss 11 formed on the propeller support 3. These hemispherical bosses 17 and 11 in addition to reducing the frictional bearing surface between the propeller 17 and its support 3 afford protective means for said propeller and its shaft when it crashes into an object; for example, in a crash where the impact occurs at the end of one of the blades 19. A bending moment is transmitted through blade 19 and central portion 21 to the shaft 15. This bending moment is however, deterred and does not bend or otherwise harm the propeller since said propeller is free to move under the force of the impact by virtue of the rolling contact between the bosses 17 and 11.

The method of attaching the propeller shaft 15 to the propeller is novel, in that it requires no welding, soldering or the like. A piece of wire has formed therein a pair of loops 31 of the conformation shown in Fig. 9. The one end of the wire is cut, as at numeral 33, in front of the propeller, while the other end 35 extends backwardly in a direction normal to the plane of the loops 31. The end 35 is inserted into the hole 25, and the loops 31 placed in position over the tabs 39. The tabs 29 are then bent firmly downward to hold the shaft 15 rigidly to the propeller 17. This engagement is more clearly shown in Fig. 10. The end 35 of the shaft 15 is then formed into a hook 37.

40 A landing gear saddle 39 is shown in Fig. 7, where it will be seen that it comprises a strip 41, preferably of stamped metal (aluminum being desirable because of its lightness), with end extensions 43 bent downwardly at right angles to said strip 41. Centered in the extensions 43 are square holes 45, which are slightly larger in area than the cross section of the fuselage 1.

Referring again to Fig. 4, there is illustrated at numeral 47 a V-shaped landing gear support, which is preferably die-cut from fiber or other semi-flexible material. Two of these supports 47 are provided, one for each side of the fuselage 1, as illustrated in 55 Figs. 1 and 3. At the top of the supports 47 are a pair of horizontal extensions 49. At the bottom of the V is provided a hole 51 to accommodate the bolt 53 which holds a landing wheel 55 to the support 47. Washers 60 57 are between the bolt-head 53 and the wheel 55, between the wheel 55 and the support 47, and between the support 47 and a nut (not shown) on the end of bolt 53, to ensure free rotatability of the wheel 55.

65 It will be noticed in Fig. 3 that the land-

ing gear supports 47 are slightly bowed so that the wheels 55 are more nearly vertical than they would ordinarily be. This bowed effect is introduced by making the width at the top of the V-shaped supports 47 greater than the length of the saddle 39.

The supports 47 and the wheels 55, together with the attachments thereto, constitute the landing gear of the airplane.

At numeral 59 in Fig. 1 are shown the wings of the airplane. The wings, made as one piece, are substantially rectangular in shape, with rounded ends. The interior construction of the wings is novel, permitting unusual strength with exceptional lightness of weight. It will be seen from Fig. 1 that a framework 61, preferably of thin, tough wood is provided. The framework comprises leading edge braces 63, trailing edge braces 65, end struts 67 and cross or lateral struts 69. While only one lateral strut 69 is shown in Fig. 1, it is to be understood that any number may be provided, depending upon the size of the wing. The braces 63, 65, 67 and 69 are all die cut from a single piece of wood, with the grain running lengthwise with the wing. It is to be understood that light, tough fiber or the like may be substituted for wood in the framework 61.

Completely enveloping the framework 61, on both sides thereof, is glued or otherwise affixed the paper or other covering material 71. The covering material 71 is preferably tough and strong, and light in weight. It is stretched tightly over the framework 61 before gluing. The covering 71 may have printed thereon advertising legends, designs or the like, thereby rendering the airplane more attractive to the eye. A protective taping 72 is securely fastened around the center of the wings 59 to prevent unusual wearing of said wings.

The framework 61 is slightly bent near the middle thereof so that the wings 59 make a slight dihedral angle with each other. This dihedral angle aids in sustaining flight over comparatively long periods of time, and in stabilizing the airplane while in flight. Similarly, the wings may be warped slightly from leading to trailing edge, giving them a camber such as the wings of real airplanes have. This camber of the wings aids said wings in increasing their lifting power.

It is to be noted that the wings 59 have a high aspect ratio (the aspect ratio being defined as the ratio of the span, or total length, of the wings, to their chord, or maximum distance from leading edge to trailing edge). A high aspect ratio is desirable in airplanes which travel at a comparatively low rate of speed, as is the case with the present toy airplane.

At numeral 73 in Fig. 1 is illustrated a stabilizer. The stabilizer 73 is shaped similarly to the wings 59, but is considerably

- smaller in size. The stabilizer 73 may be constructed in the ribbed manner of the wings 59, or it may be die-cut from a solid piece of fiber or wood or the like. A notch 75 divides the rearward portion of the stabilizer 73 into two sections 77, which simulate elevators on real airplanes. The function of the stabilizer 73 is to keep the airplane from tilting to a vertical position in flight by 5 keeping the tail up. In other words, the stabilizer maintains the longitudinal stability of the airplane, while the dihedral angle, camber, and aspect ratio of the wings 59 tend to preserve the lateral stability.
- 10 In Fig. 5 is shown at numeral 79 a rudder. The rudder 79 is approximately trapezoidal in shape, with the upper end rounded. It is preferably composed of a thin wood frame 81, covered by a paper or other covering material 83 on all sides thereof, in the same manner as the wings 59 are covered. At the bottom of the rudder 79 are affixed on each side by means of staples 85, one of a pair of supports or guides 87. These guides 87 are short 15 pieces or strips of wood. They extend forwardly of the rudder 79, and have notches 89 therein to engage a saddle 91 to be described. These guides 87 are shown in plan in Fig. 6.
- 20 The tail piece is shown at numeral 93 in Figs. 2, 5 and 6. It comprises a piece of spring wire, bent as shown in these figures to encircle the fuselage 1 with a loop 95, to form a hook 97, and to form a skid 99. The resiliency of the wire, which is nevertheless quite stiff, permits a landing of the airplane without appreciable jar, as will be described hereinafter.
- 25 Wire saddles 91 and 101 are provided for affixing the stabilizer 73 and wings 59, respectively, to the fuselage 1. In Fig. 8 is shown a perspective view of the saddle 91. The saddle 101 is similar to the saddle 91, except as hereinafter provided. The saddles 91 and 101 are 30 substantially U-shaped, with right angle extensions 103 from the legs of the U. At the ends of the extensions 103 are hooks 105. The distance between the legs of the U is approximately the width of the fuselage, while the 35 length of the legs of the U is the sum of the thickness of the fuselage 1 and the thickness of the wings 59 in the case of saddle 101, and the sum of the thickness of the fuselage 1, the thickness of the stabilizer 73, and the 40 thickness of the rudder supports 87 at the notches 89 in the case of saddle 91.
- 45 The airplane is assembled in the following manner:
- 50 The landing gear saddle 39 is first placed in position on the fuselage 1 by inserting the rear end of said fuselage 1 into the holes 45 in the extension 43, and moving said saddle 39 forwardly until it nearly touches the permanently mounted propeller support 3, as 55 shown in Fig. 4. Next a rubber band, such

as indicated at numeral 107 is hung freely around the fuselage 1 and the saddle 39.

The V-supports 47 are now placed in position by inserting the horizontal extensions 49 into the holes 45 in the extensions 43 of the landing gear saddle 39. One V-support is placed on each side of the fuselage 1. The wheels 55 are mounted on the V-supports 47 as hereinbefore described.

The V-supports 47, now in position on the fuselage 1, are spread apart as indicated in Fig. 3. This positioning enables them to hold the plane in upright position, and provides a resilient landing gear, which, by reason of its flexibility, prevents sudden shocks, such as occur in crashes, from reaching the more delicate wings and the like.

The wings 59 are next placed in position by laying the center thereof, covered by the protective tape 72, on the top of the fuselage 1, with the dihedral angle facing downwardly, as shown in Fig. 3. The saddle 101 is now hooked on to the fuselage 1 at the trailing edge of the wings 59, with the U-portion facing upwardly and the extensions 103 lying forwardly on top of the wings 59. The free hanging rubber band 107 is now drawn up, across the top of wings 59, and hooked on to the hooks 105 of the extensions 103. Thus the wing 59 is resiliently but firmly fixed to the fuselage 1.

The tail piece 93 is placed in position on the fuselage 1, with the hook 97 facing backwardly and the skid 99 dragging.

Next the tail assembly is completed. The rudder 79 is placed in position on top of the fuselage 1, in the same plane and extending upwardly from said fuselage. The saddle 91 is hooked, U-portion downwardly, extensions rearwardly, over the notches 89 in the rudder supports 87. The stabilizer 73 is then placed in position beneath the fuselage 1, and beneath the rudder 79, the notch 75 facing backwardly and the stabilizer 73 per se being between the fuselage and the extensions 103 of the saddle 91. A rubber band 109 is now hooked onto the hooks 105 on the extensions 103 of the saddle 91, and drawn backwardly under the stabilizer 73 and hooked on to the fuselage 1; thus securing the stabilizer 73 and the rudder 79 resiliently but firmly to the fuselage 1.

The propeller shaft 27 is now inserted through the hole 25 of the propeller support 3 on the front end of the fuselage 1. A number of heavy rubber bands or the like, such as indicated at numeral 111 in Fig. 2, are now placed over the hook 37 of the propeller shaft 15, and over the hook 97 of the tail piece 93. The stretched rubber bands 111 form the motive power for flying the airplane.

It will be seen that, while idle, the airplane rests on the wheels 55 and the skid 99.

Motive power for flying the airplane is

supplied by revolving the propeller 17 in the proper direction (depending upon the pitch direction of said propeller), thus twisting the elastic rubber band motor 111, and storing up a twisting force therein. After sufficient winding, the propeller is released and allowed to rotate under the influence of the elastic band 111 and pulling the airplane into the air. Ordinary flying is accomplished in such a manner.

Change of direction in the vertical plane is achieved by longitudinally varying the positioning of the wings 59 on the fuselage 1. By moving the wings 59 forwardly, the center of gravity of the plane moves forward, and the vacuum pull is greater on the top of the wings 59, causing the airplane to climb. If the wings 59 are placed too far toward the front, the plane will either "loop the loop" or stall. When, on the other hand, the wings 59 are moved toward the rear, the center of gravity moves rearwardly, giving a lesser vacuum pull on the top of the wings 59, thereby causing the airplane to dive. The relative spacing for sustained horizontal flight varies with the airplane, but it is generally of the nature of that shown in Fig. 2.

Change of direction in the horizontal plane, or turning, is accomplished by rotating the rudder 79, which is held to the fuselage by the saddle 91 only. Such a change in rudder direction is illustrated in dotted lines in Fig. 6. Pushing the rear end of the rudder to the right will cause the airplane to turn to the right, and pushing the rudder to the left will cause a turn to the left.

It will thus be seen that control of direction is had in both the vertical and horizontal planes. By combinations of the two controls, the airplane can be made to perform many attractive stunts, such as "wing overs", "spirals", and "tail spins".

The resilient construction, obtaining its chief expression in the landing gear, skid, the propeller and its mounting, and the methods of fastening the wings and stabilizer to the fuselage, protects the airplane from serious injury resulting from crashes: most crashes resulting only in a temporary displacement of parts which is instantaneously and easily repairable.

It will be noted that the wings and stabilizer provide excellent space for advertising legends, designs and the like.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

We claim:

1. In combination, as a toy airplane, a fuselage, a propeller support on said fuselage, a propeller rotatably mounted on said support, a tail piece mounted on said fuselage, propelling means connecting said propeller and said tail piece, a shaft for said propeller passing through said propeller support and connecting with said propelling means and means on said propeller comprising a pair of pressed tabs for fastening said propeller shaft to said propeller. 75

2. In combination adapted for use in toy airplanes, a propeller, a propeller support and a propeller shaft, said propeller having blades and a central portion, said central portion having at least two pressed parallel longitudinal ribs therein adapted to strengthen said propeller, a pair of tabs in said central portion positioned between said ribs adapted to engage said shaft whereby said shaft is bent to brace said propeller, a hemispherical boss pressed in the central portion of said propeller and a second hemispherical boss pressed in said propeller support, said bosses engaging to permit rolling contact between said propeller and said propeller support, said bosses being adapted to permit passage of said propeller shaft. 80 85

3. The landing gear for toy airplanes comprising a saddle adapted to engage the fuselage of a toy airplane, a pair of V-supports, said supports having horizontal extending tabs at the top of the V's adapted to engage said saddle, said supports being wider at the top of the V's than the length of said saddle, whereby said supports are caused to bow when they are positioned with said tabs in said saddle, and wheels rotatably mounted at the bottom of said V-supports. 90 95 100

4. The landing gear for toy airplanes comprising a saddle adapted to engage the fuselage of a toy airplane, a pair of resilient V-supports, said supports having horizontal extending tabs at the top of the V's adapted to engage said saddle, said supports being wider at the top of the V's than the length of said saddle, whereby said supports are caused to bow when they are positioned with said tabs in said saddle, and wheels rotatably mounted at the bottom of said V-supports. 105 110 115

In testimony whereof, we have signed our names to this specification this 20th day of December, 1929.
